(57) **CLAIM**

The ornamental design for a squeegee, as shown and described.

DESCRIPTION

FIG. 1 is a perspective view of a squeegee embodying this invention;

FIG. 2 is a top view of the squeegee shown in FIG. 1;

FIG. 3 is a front view of the squeegee shown in FIG. 1;

FIG. 4 is a right side elevation view of the squeegee shown in FIG. 1;

FIG. 5 is a rear view of the squeegee shown in FIG. 1;

FIG. 6 is a left side elevation view of the squeegee shown in FIG. 1; and,

FIG. 7 is a bottom view of the squeegee shown in FIG. 1.

The structure shown in broken lines in FIGS. 1 and 3–6 is for illustrative purposes only and forms no part of the claimed design.
